UNITED STATES PATENT OFFICE

2,141,916

HOSE FOR WASHING MACHINES

Timothy A. Johnson, Milford, Conn., assignor to
General Electric Company, a corporation of
New York

Application August 15, 1936, Serial No. 96,233

1 Claim. (Cl. 138—49)

The present invention relates to hose for use with washing machines equipped with pumps to discharge liquid therefrom.

It has been customary to provide the drain 5 hose for pump equipped washing machines with a hook-shaped metal portion or goose-neck at the discharge end for the purpose of supporting the hose on the edge of a receptacle such as a sink. Since the metal goose-neck is rigid it is necessary to provide a swivel connection 10 between it and the hose, and it is further necessary to pack this swivel connection to prevent leakage. With this construction there is also some likelihood that the metal goose-neck may 15 strike the washing machine tub or the receptacle into which the hose is discharging and thereby injure the finish.

The object of my invention is to provide an improved construction for drain hose for washing machines which will overcome the disadvantages enumerated above. For a consideration of what I believe to be novel and my invention attention is directed to the accompanying description and the claim appended thereto.

25 In the accompanying drawing, Fig. 1 is a perspective view of a washing machine equipped with a drain hose embodying my invention; Fig. 2 is a fragmentary view showing the pump connected to the bottom of the washing machine tub 30 and to the drain hose; and Fig. 3 is an enlarged sectional elevation of the hook-shaped end of the drain hose.

Referring to the drawing, there is shown a washing machine having a tub 1 provided with 35 a drain opening 2 in its bottom wall which is connected to the inlet 3a of a pump 3. The pump is driven through a pulley 4, for example by the motor (not shown) which drives the washing machine. The outlet 5 of the pump is 40 connected to one end of a flexible hose 6 made of rubber or other material having the properties of rubber. The discharge end of the hose is molded in the form of a hook-shaped portion or goose-neck 7. Since the goose-neck is integral 45 with the hose there is no joint between the goose-neck and the hose which will require

packing. Due to the inherent properties of rubber the goose-neck is self-sustaining in that it normally assumes the position shown, but, if necessary, can be temporarily bent in any direction from this position and, when released, 5 will return to its normal position. For example, the arm 7a of the goose-neck may be twisted about the arm 7b in either direction through an angle of 180°, thus securing the results obtainable with a swivel joint, or the arm 7a may be 10 bent outward away from the arm 7b, thus increasing the space between the arms of the goose-neck, and when released the goose-neck will return to its normal position. The goose-neck is sufficiently rigid so that when hooked 15 over the edge of a receptacle it will support the hose. The arm 7a of the goose-neck may also be bent by the operator to direct the stream discharged from the hose in any desired direction. Another advantage of this hose construction is 20 that it has no metal parts to strike against the washing machine tub and injure the finish.

Fig. 1 shows one manner of using the drain hose. When the washing machine is not in use the goose-neck is inserted through an opening 25 8 in the cover 9, thereby holding the hose in the full line position. When the hose is used to discharge liquid from the washing machine the goose-neck is hooked over the edge of a receptacle, such as a sink 10 as shown in dotted 30 lines, and supports the hose for discharge therein.

What I claim as new and desire to secure by Letters Patent of the United States, is:

In a washing machine or the like having a pump for pumping liquid therefrom, a flexible 35 hose of rubber like material adapted to be connected at one end to the outlet of the pump and at the other end being permanently formed into a hook-shaped portion, said hook-shaped portion being self-sustaining in that it will return 40 to its normal shape after being bent in any direction and having sufficient rigidity to support the hose over the edge of a receptacle for discharge therein.

TIMOTHY A. JOHNSON.
